UNITED STATES PATENT OFFICE.

HARRY D. LILLIBRIDGE, OF ZANESVILLE, OHIO, ASSIGNEE TO AMERICAN ENCAUSTIC
TILING COMPANY, LTD., OF NEW YORK N. Y., A CORPORATION OF NEW YORK.

SANITARY TILE-SPRAYING CHAMBER.

1,223,810.

Specification of Letters Patent. Patented Apr. 24, 1917.

Application filed July 28, 1913. Serial No. 731,501.

To all whom it may concern:

Be it known that I, HARRY D. LILLIBRIDGE, a citizen of the United States, residing at Zanesville, county of Muskingum, 5 and State of Ohio, have invented a certain new and useful Sanitary Tile-Spraying Chamber, of which the following is a specification.

This invention is a sanitary spraying chamber embodying means for precluding workmen engaged in, or adjacent to, said chamber from inhaling air which is filled with certain matter more or less injurious to health, which matter may be in the nature 10 of a glazing solution to be applied in the form of a spray to ceramic tiles or other products for decorative effects and other purposes.

It is well known that certain classes of 20 labor subjects or expose the workmen to the risk of inhaling air laden with fumes and vapors deleterious to health, so that in recent years sanitary regulations have been adopted and enforced whereby workmen 25 are rendered immune to a certain extent while engaged in such operations.

The present invention is useful, more particularly, in the ceramic industry wherein 30 it is a common practice to apply coloring matter to tiles, etc., by spraying such matter upon the surfaces thereof. This operation when conducted in a factory room, wherein a number of persons are engaged at work, exposes all of them to the injurious effects 35 of a more or less poisonous matter, particularly in case the air of the room becomes charged with the sprayed liquid. This objection is not overcome even though the room is well ventilated, nor is it obviated 40 by exhausting the air by the act of artificial ventilation, for the reason that the compressed air employed to convert the liquid into a spray is under considerable pressure, so that the liquid spray is thrown into all 45 parts of the room, and furthermore, the spray is thrown with such force against the tiles or other objects that some of it rebounds and strikes the operator's face and person.

According to this invention, means are 50 provided for absorbing all the sprayed matter which does not adhere to the tiles or other work under treatment in such manner that the waste spray cannot charge or fill the air within the room. For the best results, it is found advisable to conduct the 55

spraying operation in a separate room closed against communication with another room or rooms except to receive the necessary supply of air therefrom, and to exhaust the air from such spraying room by 60 artificial means, to the end that a flow of air will be established through the spraying room, and around the workman and the work, whereby the spray not taken up by the absorbing medium and which may re- 65 bound more or less from the tiles or other objects will be caught up by, and carried off with, the air current.

It is to be understood that the work of spraying is conducted by placing the object 70 between the spray absorbing medium and the workman, and by directing the spray toward the object and said absorbing medium, whereby any spray which passes beyond the object will be taken up by said absorbing 75 medium. Various substances may be used as the absorbing medium, such as a suspended wet fabric, but for efficiency and economy it is preferred to use a thin film or sheet of running liquid, such as water, the flow of 80 which is continuous. In a practical form, a background of glass, or the like, is employed, and a horizontal perforated pipe is positioned at or near the top edge of this background, suitable connections being made 85 with a source of liquid supply, whereby a relatively thin sheet or film of continuously flowing liquid is maintained between the work and the background. The liquid spray thrown toward or against this absorbing 90 medium is at once taken up by or dissolved in the liquid, the flowing liquid being collected by a suitable trough or gutter having connections with a sewer or other outlet.

Other features of the invention and the 95 advantages thereof will appear from the following detailed description.

In the drawings,

Figure 1 is a sectional plan view illustrating a spraying chamber equipped with 100 means embodying the present invention.

Fig. 2 is a vertical section on the line 2-2 of Fig. 1.

Fig. 3 is a vertical section taken in a plane at right angles to Fig. 2, showing the hood 105 and other parts in elevation.

Fig. 4 is a side view of one corner of the spraying chamber, illustrating a ventilator by which air is admitted to the spraying chamber from another apartment.

2
Fig. 5 is an enlarged detail view through one ventilator.

Fig. 6 is an enlarged detail view showing means for spraying liquid against the panel or background.

A designates a chamber or compartment within which the operation of spraying tiles, objects of ceramic ware, or any other work may be carried on. As shown, the chamber 10 A is adjacent to other rooms or apartments a a', (one or more) and the walls b of said spraying chamber are provided with windows b' for the purpose of lighting this chamber, access to which is obtained through 15 a door b''. The floor c of the spraying room is preferably composed of concrete, tiles or other non-absorbent material, and the upper surface of this floor is inclined toward a drain c' from which leads a waste pipe c'', the latter being connected with a waste drain 20 B adapted to discharge waste liquid matter into a sewer or otherwise. The spraying room is equipped with means for conducting the spraying operation; as shown a stand 25 or table d is provided in one corner, and upon this stand is positioned a compressed air tank C equipped with a suitable gage d'. Connected to the tank is a supply pipe d'' leading from an air compressor, so that the 30 tank C may be charged with air to the desired pressure. The tank is shown as having an outlet pipe C' to which may be connected a hose leading to a spraying device, the latter being supplied with a liquid coloring 35 matter in the usual way, so that the air will convert the liquid into a spray adapted to be thrown against the surface of a tile or other object to be treated. The work to be decorated or otherwise treated may be supported in any suitable way within the spraying 40 chamber. I may provide a rack of special design for holding the pieces of ceramic tile, but the work holding means shown in Figs. 2 and 3 consists of a table E provided 45 with a rotatable top e. It is obvious that the work is placed upon the rotatable top so as to be supported in front of the workman, thus making it convenient for the operator to direct the spray against the objects resting upon the top e, it being possible to rotate 50 the top in order to present the edges or all sides of the object to the spray. For the convenience of the operator the spraying chamber may be equipped with sanitary plumbing, such as the basin F and water faucet f.

Positioned within the spraying chamber is a hood G, the same being preferably of arched form in longitudinal section and substantially rectangular form in plan. This 60 hood is directly over the work supporting rack or table, and beneath the hood is carried on the operation of spraying the coloring matter upon the tiles or other objects. The hood is supported by any suitable means 65 within the spraying chamber, and for this

purpose I have shown said hood as being suspended by cords or chains g from the ceiling of the chamber. The hood is composed, preferably, of sheet metal, such as sheet steel, and if desired the surfaces of the metal may be enameled or otherwise finished so as to produce a surface easily cleaned by washing it. It is preferred to employ a hood the sides and ends of which are provided with transparent panes g' of glass or other material, said panes of transparent material being inserted in suitable openings provided in the hood and being attached firmly thereto by appropriate means. Within the hood are provided suitable lighting means, such as the incandescent electric lamps G'. The transparent panes of glass and the electric lamps afford means for illuminating the work supported on the rack or table below the hood. Obviously, illuminating means other than the electric lamps G' may be employed, and if desired the interior of the room may be lighted by one or more other lamps G''.

Extending from the hood is an exhaust flue H, one end portion of which is attached to the hood for the purpose of receiving air from the lower or under side of the hood. This exhaust flue leads out of the spraying room A through one of the walls thereof so as to discharge the air at any suitable place. Suitable means are provided for creating a draft of air through the hood and the flue in order to exhaust the air from the room, and in Fig. 3 said exhausting means is represented by dotted lines as a fan or blower H'.

An important feature of the invention consists of ventilators I in one or more walls of the spraying chamber A. It is preferred to provide ventilators in at least three walls of the spraying chamber in order that the air may flow in all directions from the walls of the chamber toward the operator stationed below the hood, the air being drawn from several directions toward the hood so as to envelop the operator and the work in a zone of air, for the purpose of carrying away from the operator all the spray which may rebound from the tiles or other objects. The ventilators may be of any suitable construction, but it is preferred to employ a ventilator with pivoted blades i. Said blades are so hung that the ventilator will open by the draft of air drawn through the room by the action of fan H', but should a draft of air take place in an opposite direction the blades of the ventilator will automatically close, thus precluding air laden with coloring matter from flowing out of the room and through the ventilators into an adjacent compartment a or a', whereby the workmen engaged in rooms other than the spraying room will not be exposed to the spray laden air from said spraying room.

J designates a background extending downwardly from the suspended hood and positioned so as to intercept the spray from the spraying device thrown toward or upon the objects which rest on the work table E. 5 This background is composed, preferably, of wired glass in order to afford the desired illumination of the room, but, obviously, any other material suitable for the purpose 10 may be employed. The background is of suitable width and height, and it is supported in a fixed position by appropriate means, such as the bracket j, fastened to one wall of the room, see Fig. 2. The upper edge of the background is positioned preferably within a lower edge of hood G, substantially at the rear thereof.

Coöperating with the background is a pipe K for supplying water to one surface 20 of the background, said pipe being positioned preferably at or near the upper edge of background J. The pipe extends horizontally for substantially the full length of the background, as shown in Fig. 1, and to this pipe is connected a supply pipe k which 25 leads outside of the spraying room so that the pipe k will supply the faucets f to one or more basins F. It is preferred to employ a filter K' in connection with a supply pipe 30 k, and this filter is provided with a by-pass k². The filter is in the line of flow of the water to be supplied to pipe K so as to remove sediment from the water, and the by-pass enables the water to be sent through the filter for the purpose of flushing the latter. 35

The distributing pipe K is preferably provided with openings arranged to direct streams of water against the front surface 40 of the background, thereby producing a film or curtain of continuously flowing water. Said film or curtain operates primarily to absorb the coloring matter of the spray which eludes or passes the object under treatment, but the film or curtain acts, also, 45 to flush the surface of the background and thereby wash away any coloring matter which may adhere to said background.

Below the background is positioned a collecting trough L into which flows the 50 water supplied to the background by the distributing pipe. This collecting trough is open at the top side and extends the full length of the background, said trough being positioned centrally with respect to the background. A drain pipe l is connected to the collecting trough or gutter and this pipe 55 communicates with waste pipe B, thus providing for the ready escape of the water which forms the film or curtain and the coloring matter which is carried off 60 thereby.

The operation will be apparent from the foregoing description taken in connection 65 with the drawings, but may be summarized as follows: Compressed air is supplied to

tank C, and the spray device is connected with the tank and with a source of liquid coloring matter so that the operator is able to throw a spray upon the work placed on table E, the spray being directed toward the 70 background, and the film or curtain of liquid flowing over the surface thereof. The door to the spraying chamber is closed, and fan H' is set in motion, thus drawing air through ventilators I and causing the air to 75 flow in the required volume around the operator, but the spray should in all instances be directed toward the background. The sheet or curtain of water flowing over the background absorbs any coloring matter 80 in the spray which escapes the objects, but the air being supplied under pressure, some of the spray strikes against the objects and rebounds toward the workman. This rebounding spray is caught up by the current 85 of air flowing around the workman and upwardly into the hood.

It will be understood that the invention provides means for rendering the workman 90 immune to the effect of the sprayed coloring matter, for the reason that the spray which escapes the objects will become absorbed by the sheet or film of flowing water, and the spray that rebounds or flies off the objects is caught up by the air flowing through the 95 spray room and upwardly into the hood.

Various forms of apparatus may be employed for carrying into practice the method or process herein disclosed, said process being made the subject matter of a separate 100 application filed by me on even date here-with.

As shown in Fig. 3, pipes h⁴ may lead from pipe K to trough L for flushing the latter independently of the spray, the flow 105 of water through said pipes h⁴ being controlled by valves h⁵.

Having thus fully described the invention, what I claim as new, and desire to secure 110 by Letters Patent is:

1. An apparatus of the class described embodying a chamber, spraying means positioned within said chamber whereby the work of spraying objects is to be performed, means for circulating air through the 115 chamber, an absorbing medium positioned within said chamber to collect or take up deleterious sprayed matter projected by the spraying means beyond the work, and means for withdrawing air from the chamber and 120 adjacent said absorbing medium.

2. An apparatus of the class described embodying a chamber, spraying means positioned within the chamber whereby the work of spraying objects is performed, means for circulating air through the chamber, and means for establishing within such chamber 125 a liquid curtain adapted to absorb deleterious sprayed matter projected beyond the objects under treatment, said air circulating 130

means being effective in withdrawing air from the chamber adjacent the liquid curtain.

3. An apparatus of the class described embodying a chamber, spraying means within the chamber, means for admitting air to the lower part of the chamber, a spray absorbing medium positioned to intercept a spray which passes beyond the work under treatment, and means for exhausting air from the upper part of the chamber adjacent the spray absorbing medium.

4. An apparatus of the class described embodying a chamber, spraying means within said chamber whereby the operation of spraying objects with coloring matter is conducted, means for producing a continuously moving film or sheet of liquid in such relation to the work as to intercept the sprayed matter which passes said objects, and means for circulating air through the chamber and withdrawing air therefrom at a point adjacent the moving film or sheet of liquid for carrying off the sprayed coloring matter rebounding from the work under treatment.

5. An apparatus of the class described embodying a chamber within which is to be conducted the operation of spraying objects, means for producing a continuously moving film or sheet of liquid in a position to intercept the spray passing such objects, and means for circulating air through said chamber and withdrawing it adjacent the film or sheet so as to envelop the field within which is conducted the operation of spraying the objects under treatment whereby the operator within the chamber is enabled to perform the work without danger of inhaling a poisonous sprayed coloring matter.

6. An apparatus of the class described embodying a chamber, spraying means within said chamber, a background positioned within said chamber, means for establishing the flow of a sheet or film of liquid over the background whereby the sheet or film of liquid is adapted to intercept the spray passing the work to be treated, and means for withdrawing air from the chamber adjacent the liquid sheet or film.

7. An apparatus of the class described embodying a chamber, spraying means whereby a spraying operation is conducted within the chamber, a background separate from the walls of the chamber and positioned within the same, a liquid collecting member at the lower edge of said background, means for supplying a sheet or film of liquid adapted to flow over the surface of the background and into said collecting member, and means for withdrawing air from the chamber at a point adjacent the sheet or film of liquid.

8. An apparatus of the class described embodying a chamber within which a spray-

ing operation is to be conducted, a spraying device, a background separate from the walls of the chamber and positioned within said chamber, a liquid collecting trough positioned below said background, said trough having a waste discharge, and means for supplying a film of spray-absorbing liquid to flow over the surface of the background and into said trough.

9. An apparatus of the class described embodying a chamber, spraying means within said chamber, means for admitting air to the lower part of the chamber, an exhaust flue leading from the upper part of said chamber, and spray-absorbing means positioned within said chamber and adjacent the inlet to the exhaust flue for intercepting a spray passing beyond the object under treatment.

10. An apparatus of the class described embodying a chamber, a water curtain therein, and an exhaust hood the inlet to which is in the immediate proximity to said water curtain.

11. An apparatus of the class described embodying a chamber, spraying means positioned therein, and a water curtain within said chamber and in the path of the spray from said spraying means.

12. An apparatus of the class described embodying a chamber, a hood beneath which the spraying operation is to be conducted, means for exhausting air from said chamber through said hood, and a spray absorbing medium adjacent to the hood for intercepting the spray which may pass by the object under treatment.

13. An apparatus of the class described embodying a chamber, a hood beneath which the spraying operation is to be conducted, means for exhausting air from said chamber through said hood, and means for establishing a flow of a sheet or film of spray absorbing liquid adjacent to the hood and in the path of a spray which may pass by the object under treatment.

14. An apparatus of the class described embodying a chamber, an exhaust hood positioned therein, a background beneath the edge of the hood, and means for supplying a sheet or film of liquid over the surface of the background, the inlet to said exhaust hood being in proximity to the sheet or film.

15. An apparatus of the class described embodying a chamber, an exhaust hood positioned therein, an exhaust connection with said hood, a background extending downwardly from the edge of the hood, and a liquid supply pipe positioned in front of said background and under said hood.

16. An apparatus of the class described embodying a chamber, a hood, positioned therein, an exhaust connection for said hood, a background extending downwardly from the edge of the hood, a collecting member at

- the lower part of said background, and means positioned under the hood for supplying liquid to flow in front of said background and thence into said collecting member.
17. An apparatus of the class described embodying a chamber the walls of which are provided with ventilators adapted to supply air to the interior of the room, a hood beneath which the operation of spraying objects with coloring matter is to be conducted, means for exhausting air from the chamber and through said hood, and means whereby a film or sheet of liquid is maintained adjacent to said hood and in the path of the spray.
18. An apparatus of the class described embodying a chamber equipped with means for spraying objects with coloring matter,
- ventilators positioned in the walls of said room for admitting air thereto, means for establishing the flow of a sheet or film of liquid within said chamber, a hood positioned within the chamber and beneath which the spraying operation is to be conducted, said hood being adjacent said film or sheet, and means for exhausting air from the chamber and through the hood, whereby the air is withdrawn from the chamber adjacent said film or sheet.
- In testimony whereof I have signed my name to this specification in the presence of two subscribing witnesses.
